(57) CLAIM

The ornamental design for oil extractor for vehicle engines, as shown and described.

DESCRIPTION

FIG. 1 is a front elevational view of the design for oil extractor for vehicle engines;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a sectional view taken on line A—A of FIG. 1;

FIG. 8 is a sectional view taken on line B—B of FIG. 4;

FIG. 9 is a top perspective view thereof; and,

FIG. 10 is an exploded perspective view thereof.
